SINGLE CYLINDER FLUID-ACTUATED LOG TURNER

Filed March 10, 1950

2 Sheets-Sheet 2

The drawings of this application show my invention described with reference to a side view of one end of the nigger bar, the other end being substantially similar. The nigger bar can be made of any suitable material and may be rectangular in cross section and have a central longitudinal slot or opening extending the full length of the nigger bar. The nigger bar may be made of any suitable material and may be rectangular in cross section and have a central longitudinal slot or opening extending the full length of the nigger bar. The nigger bar may be made of any suitable material and may be rectangular in cross section and have a central longitudinal slot or opening extending the full length of the nigger bar.

UNITED STATES PATENT OFFICE

Patent No. 2,655,185
SINGLE CYLINDER FLUID-ACTUATED LOG TURNER
Dow C. Richardson, Metropolis, Ill.

Application March 10, 1950, Serial No. 148,794

3 Claims. (Cl. 143—101)

1

The present invention relates to log turners of the type commonly referred to as niggers, and more particularly has reference to a power operated nigger which is simple in structural detail, positive and efficient in operation and which can be readily incorporated in either fixed or portable sawmill operations.

The power operated niggers which are currently employed uniformly require that the power cylinder be located at a point beneath the lower end of the nigger bar which requires a considerable amount of space beneath the floor of the mill and the supporting surface for the power cylinders. Furthermore, in many instances there is not a sufficient space beneath the floor to accommodate the assembly and this necessitates the digging of a well or the like which is a laborious and expensive process. Additionally, in connection with portable mills, it is not feasible to make use of the power niggers, since the expense of digging the well would, in the majority of instances, not be warranted for the particular sawing operations. Accordingly, an object of my invention is to provide a power operated nigger which may be easily employed with either a fixed mill or a portable mill and which may be installed without the necessity of digging a well or providing any substantial supporting surface for the nigger and which may be placed in operative position in a minimum of time and without the services of skilled workmen.

Yet a further object of my invention is to provide a power operated log turner or nigger wherein the power cylinder and the nigger bar are mounted on a supporting assembly in substantially parallel relationship with the piston rod of the power cylinder being pivotally connected to the nigger bar intermediate the ends of the bar and the supporting assembly in its entirety being adapted to be mounted to the floor of the mill.

And yet a further object of the present invention is to provide a power operated nigger of the character described wherein the supporting assembly is suspended, so to speak, beneath the mill floor and does not require the use of a stable supporting base.

And still another object of my invention is to provide a power operated nigger wherein a pair of parallel power cylinders are supported on opposite sides of the nigger bar, the piston rods of the respective cylinders being pivotally mounted to the bar intermediate the upper and lower ends of the bar.

To achieve the above and other objects, the invention broadly comprises a stable supporting

unit including a pair of spaced apart horizontal members, the upper one of which is of greater length than the lower, and means to rigidly support the horizontal members in spaced relation, which means also functions as a guide for insuring vertical sliding movement of the nigger bar. A diagonal brace extends between the horizontal members and limits the extent of the oscillating movement of the nigger bar when the bar is in the deck, and a power cylinder is pivotally connected to the lowermost horizontal support and the piston rod thereof is pivotally attached to the nigger bar intermediate the length of the bar, the pivotal connection being at a position which will be below the mill floor when the bar is in the hole.

A source of fluid under pressure is in communication with the interior of the cylinder at points above and below the piston, and valve means provided with a control lever on the mill floor is provided to control the admission of the fluid into the power cylinder. The supporting unit and its associated members is adapted to be dropped through an elongated opening in the mill floor, preferably adjacent the log deck and is secured to the floor by suitable fastening means.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 is a view in side elevation, partly in section, of the preferred embodiment of my invention, the nigger bar being shown out of the hole.

Figure 2 is a view in side elevation, partly in section, showing the position of the nigger bar under the deck.

Figure 3 is a sectional view taken along the line 3—3 of Figure 1, the view being taken in the direction of the arrows.

Figure 4 is a view taken along the line 4—4 of Figure 1, the view being taken in the direction of the arrows.

Figure 5 is a fragmental vertical sectional view of the assembly, the lower end of the nigger bar being "in the hole" and the bottom of the bar resting on the rubber bumper.

Figure 6 is a side elevational view, partly in section, of a modified form of the invention.

Referring to Figure 1, I have identified the floor of the sawmill 10, 11 is a log carriage of conventional type riding on rails 12, 13 is a log deck, and 14 indicates generally my novel power operated nigger.

The nigger 14 comprises a horizontally extending upper member 15 which, as shown in Figure 3, includes a pair of longitudinally extending spaced angle irons 16, the rearmost ends of the irons being fast connected by a transversely extending angle iron 17, while the opposite or front ends of the irons are attached to a plate 18. The union between the irons 16, 17 and the plate 18 may be by welding or some other suitable securing processes. A pair of spaced 15 downwardly extending channel bars 19 are suitably connected to the horizontal flange of the irons 16 adjacent to the front plate 18, and the lower ends of the channel bars are conveniently attached to a horizontal plate 20 and, as shown in Figure 1, the plate 20 is of considerably less length than the angle irons 16. Another channel bar 21 is attached at its upper end to the horizontal flange of the angle iron 17 and at its lower end adjacent the rear end of the plate 20 20 for reinforcing purposes and also for serving as a stop for a nigger bar 22 when the bar is under the deck.

The nigger bar 22 comprises a pair of spaced 30 plates 23 between which a plurality of dogs 24 are pivotally attached, as indicated at 25, and pins 26 extending transversely of the bar serve to limit the downward pivotal movement of the dogs. The lower ends of the plates 23 are provided with a solid metal block 27 which is welded 35 to the plates and is provided with a plurality of opposed L-shaped members 28 which are adapted to embrace outer flange 29 of a rail section 30 which is secured to and extends longitudinally of the web of each channel bar 19 (Figures 4 and 5) to function as a guide for the nigger bar 22. It can be seen that there is sufficient clearance between the L-shaped members 28 and the flange 29 to permit sufficient angular movement of the bar to assume its under the deck position (Figure 2).

A rubber or other resilient block 31 is located on the plate 20 beneath the bar 22 to absorb the shock imparted by the bar 22 when the bar is in its lowermost or in the hole position. Similarly, a wooden block 32 is secured between the flanges of the channel bar 21 in proximity to the upper end of the bar to take up the shock when the nigger bar 22 is moved to the position illustrated in Figure 2.

In order to operate the bar 22, a cylinder 33 is pivoted to spaced ears 34 on the plate 20 by means of a pin or the like 35 and piston rod 36 for piston 37 is pivotally secured to a pair of ears 38 welded to the plates 23 by a pivot pin 39. The ears 38 are located on the plates 23 at a point intermediate the ends of the nigger bar. Ports 40 and 41 are provided in the cylinder on opposite sides of the piston 37, preferably near the upper and lower ends of the cylinder 33, and conduits 42 and 43 are connected to the ports 40 and 41, respectively. The conduits 42 and 43 lead to a four-way valve 44 to which oil is supplied through a line 45, and the valve 44 is controlled by means of a lever 46 on the floor 10 at the desired location, the lever being connected to the valve through member 47. The valve 44 may be located at any strategic point with respect to the mill.

To install the assembly 14, the floor 10 is

formed with an elongated slot 48, preferably adjacent to the log deck 13, and the slot conforms substantially to the distance between the vertical flanges of the angle irons 16. The unit in its entirety is then dropped through the slot 48 and the horizontal flanges of the angles 16 and the rear angle iron 17 will rest on the floor 10. Suitable securing means such as bolts or the like may be inserted through spaced openings in the horizontal flanges and the floor to anchor the assembly to the floor. Hence, it can be seen that the nigger may be very easily and quickly installed in the mill or removed from the mill, if necessary. By virtue of the relationship of the power cylinder 33 relative to the nigger bar 22, it is unnecessary that the bar be of any substantial length and the overall dimensions of the assembly will enable it to be installed in the majority of fixed and portable mills without any material modification of the mill structure or the necessity of digging a well or pit below the nigger. In certain types of portable mills where the floor is very close to the ground surface, it may be necessary to dig a comparatively shallow pit to accommodate the assembly. However, experience has demonstrated that rarely is this pit more than two feet in depth.

The elimination of the well or pit is a very desirable feature since the pits often become filled with debris from the sawing processes as well as water, and hence, frequently require cleaning. This not only is a very time consuming process, but most expensive, and by virtue of the mode of attachment of the present nigger to either the fixed or portable mill, the pit or well is unnecessary.

In view of the fact that the operation of the nigger bar will be readily apparent to one skilled in the art, it is not deemed necessary to describe in detail the manner in which the nigger is employed. However, it can be seen that by manipulation of the control lever, the fluid can be admitted to the lower end of the cylinder to raise the nigger upwardly out of the hole and the nigger can be held in any desired position by the operator. By admitting fluid into the upper end of the cylinder, the nigger bar can, of course, be moved to a position under the deck by reason of the pivotal mounting of the power cylinder to the horizontal plate 20.

It will be appreciated, therefore, that the log turner includes few essential working parts and is very sturdily constructed. The unit by reason of its suspended support beneath the floor of the mill is readily accessible for servicing and maintenance and in the event it has to be removed from the mill, this can be very simply and relatively inexpensively accomplished.

In certain sawing operations such as quarter sawing, I find that the power operated assembly illustrated in Figure 6 is particularly effective in that one-half of the log upon which it is not desired to work can be moved onto the log deck. In view of the similarity between this unit and the principal embodiment, the same reference characters are applied to the corresponding parts. However, in this unit it will be noted that the lower horizontal plate 20 extends beyond the channel bars 19 as indicated at 50 and a power cylinder 51 is pivoted to the extension 50 as shown at 52. The cylinder, of course, is provided with a piston and piston rod 54 is pivotally mounted at its free end to spaced ears 55 as denoted at 56 and the ears 55 are opposite the ears or lugs 38. Lines or conduits 57

and 58 communicate with the interior of the cylinder 51 near the upper and lower ends, respectively, and the opposite ends of these lines are operatively connected to the valve structure 44.

In view of the fact that the ears 55 will be above the floor when the nigger bar is out of the hole, it is necessary that the plate 18 secured to the front ends of the angles 16 be modified somewhat. The desired results may be achieved by welding a plate to each angle iron and the inner ends of the plates will be spaced apart to provide a slot or opening of sufficient size to permit the piston rod 54 to extend therethrough. Manifestly, by manipulation of the control lever, the cylinder 51 may be utilized to move or slap one-half of the log back onto the deck for subsequent processing.

It can be seen that the nigger bar when standing in the hole at its forward position will be out of the way when the log is traveling into the saw. Additionally, when the bar is back in the deck, it will be in the hole sufficiently to permit the logs to pass or roll over the bar without striking the bar in the idle position.

In the event the log turner is to be set on the ground, a skid can be disposed underneath each of the angle irons 16 and the irons bolted to the skids.

While I have specifically referred to oil as the medium for operating the power cylinders, it is, of course, understood that steam, air, or other fluids may be employed in lieu thereof.

The invention is not to be confined to any strict conformity with the showing in the drawings, but may be changed or modified so long as such changes or modifications mark no material departure from the salient features of the invention as expressed in the appended claims.

I claim:

1. In a log turner for sawmills, a pair of spaced horizontal angle irons, means secured to the front and rear ends of the angle irons for maintaining the angle irons in spaced relationship, further means for attaching said angle irons above an opening formed in the sawmill floor, a pair of spaced downwardly extending channel bars secured to said angle irons adjacent the front ends of the angle irons extending downwardly through the floor opening, a plate attached to the lower ends of the channel bars, said plate being of lesser length than the angle irons, a brace secured at one end to the rear of the angle irons and extending downwardly through the opening in the floor, means securing the opposite end of the brace to the plate, a track on said spaced channel bars, a nigger bar slidably and oscillatably mounted on said track, a cylinder pivotally connected to said plate and disposed in spaced

relation to the nigger bar, a pivotal connection between the cylinder piston rod and the nigger bar intermediate the ends of the nigger bar, valve means to admit fluid into the cylinder, and a control lever operatively connected with said valve to operate said valve.

2. In a log turner as claimed in claim 1 wherein a resilient block is mounted on said plate below said nigger bar to absorb the shock of the nigger bar.

3. In a hydraulic log turner for sawmills, a pair of spaced horizontal angle irons, means attached to the front and rear ends of the angle irons to maintain the said irons in spaced relation to form an elongated slot therebetween, further means securing the said irons above an opening in the sawmill floor with the slot in communication with the opening, a pair of spaced downwardly extending rail members secured to the angle irons adjacent the front ends of the irons extending downwardly through the slot and opening, a base plate attached to the lower ends of the rail members, a brace affixed to the plate in spaced relationship to the rail members and extending upwardly from the base plate, means securing the free end of the brace to the rear of the angle irons, a nigger bar, complementary means on the nigger bar and the rail members whereby the bar is guided on the rail members for sliding and oscillating movement, a cylinder pivotally connected to the base plate for movement about a horizontal axis, the pivot connection being in spaced relation to the said nigger bar, a pivot connection between the piston rod in the cylinder and the nigger bar in proximity to the upper end of the said bar, a source of fluid, conduits between the fluid source and the cylinder, valve means interposed in the conduits to control the fluid flow to and from the cylinder, and a control means to actuate the valve means operatively connected to the valve means.

DOW C. RICHARDSON.
